UNITED STATES PATENT OFFICE.

THOMAS H. SEELEY, OF BOSTON, MASSACHUSETTS, ASSIGNEE, BY MESNE ASSIGNMENTS, TO UNITED SHOE MANUFACTURING CORPORATION, OF PATERSON, NEW JERSEY, A CORPORATION OF NEW JERSEY.

SEWING-MACHINE.

1,248,901.

Specification of Letters Patent. Patented Aug. 10, 1920.

Application filed September 25, 1916. Serial No. 122,002.

To all whom it may concern:

Be it known that I, THOMAS H. SEELEY, a citizen of the United States, residing at Dorchester, Boston, in the county of Suffolk and State of Massachusetts, have invented certain new and useful Improvements in Sewing-Machines; and I do hereby declare the following to be a full, clear, and exact description of the invention, such as will enable others skilled in the art to which it appertains to make and use the same.

This invention relates particularly to the problem of applying a heat-retaining and protective casing to a shoe-sewing machine of the type in which the work is presented to operative instrumentalities at the front of the machine, though it will be apparent that, in certain aspects, the invention is applicable to sewing-machines of other types.

A general object of the invention is to provide, for a machine of the type above referred to, a casing, including a front cover, which shall be effective for the intended purposes but which shall not interfere with the presentation of the work to the machine, or render less convenient the incidental operations involved in the use of the machine, particularly the operations of replenishing the locking-thread and of releasing and raising the presser-foot or other work-holding device.

With relation to the replenishment of the locking-thread, the foregoing object is attained by unifying, with the front-cover of the casing, the means by which the shuttle, bobbin-case, or other device for holding the locking-thread is retained in its race or receptacle. By this arrangement the structure is rendered compact, and the operation of opening the combined cover and retainer is merely substituted for the usual operation of moving the retainer alone.

With relation to the presser-foot mechanism, the invention is particularly applicable to machines having presser-foot mechanism in which two distinct manual operations are required in releasing and raising the presser-foot. An object of the invention is to provide means by which these two operations may be performed through a single movement of a single manually-operable member, and in the preferred embodiment of the invention this manually-operable

member is mounted on the front-cover and is accessible without opening the cover.

Other objects of the invention, and the features of construction by which they are attained, are set forth in connection with the following description of the illustrated embodiment of the invention.

In the accompanying drawings, Figure 1 is a front-elevation of a sewing-machine embodying the present invention. Fig. 2 is a side-elevation of the same machine, with the front-cover closed. Fig. 3 is a side-elevation with the front-cover open. Fig. 4 is a front-elevation of the presser-foot mechanism, on a larger scale than the preceding figures. Fig. 5 is a detail plan-view, showing parts of the presser-foot mechanism. Fig. 6 is a side-elevation of the presser-foot mechanism, on the same scale as Fig. 4, showing the parts in their normal position. Fig. 7 is a similar side-elevation, showing the parts in the position assumed when the presser-foot is released and raised.

The invention is illustrated as embodied in a machine for stitching the outer soles of shoes, this machine being, in its principal features, that which is disclosed in United States Letters Patent No. 473,870, granted April 23, 1892, to Z. T. French and W. C. Meyer. This machine is adapted to produce a lock-stitch seam, being provided with a loop-taker in the form of a shuttle 10, which moves in a shuttle-race 12 at the front of the machine. The locking-thread is contained within a bobbin-case 13, which is removably inserted in a recess in the front of the shuttle. The work is supported on a work-support 14, and is held firmly against the work-support by a presser-foot 16. The various mechanisms of the machine are actuated by means of a cam-shaft 18 carrying cams of appropriate form. All of these

features of construction are among those which are disclosed in the said Patent No. 473,870, and the well known construction of the machine will not be further described except in so far as it is necessary for an understanding of the present invention.

The upper part of the machine is inclosed by a casing of which the main portion 20 is stationary, while the forward portion is in the form of a door or cover 22. Most of the forward portion of the machine is in-

closed by the cover 22, but it is cut away wherever operative instrumentalities of the machine must be exposed, or where there is not sufficient clearance, between the mechanism and the shoe which is operated on, to permit the introduction of a casing without interference with the movements of the shoe. The cover is normally closed, but it is hinged, at one side, so that it may be 10 swung away from the front of the machine to afford access to the inclosed parts. For this purpose the cover is provided with lugs 24 pivoted to lugs 26 projecting from the body 20. The body is fixed stationary, in 15 any convenient manner, upon the frame 28 of the machine. In order that the cover 22 may be normally retained in closed position, it is provided with a spring-pressed latch 30 at the top, which co-operates with a 20 lug 32 on the forward edge of the casing.

As in said Patent No. 473,870, the bobbin-case is retained in the shuttle, and is prevented from oscillating with the shuttle, by means of a retainer 34 (Fig. 3) provided 25 with a recess 36 to receive the nose of the bobbin-case. In the present instance, however, this retainer is not provided with special means for operating and supporting it, but the construction is simplified and 30 rendered compact by mounting the retainer upon the cover 22 so as to unite it therewith. Owing to this arrangement the mere act of opening the cover releases the bobbin-case, so that it may be removed if desired, and at 35 the same time the arrangement permits the cover to be brought closer to the front of the machine than would be possible if it were necessary to provide space, within the cover, for the means usually employed to support 40 and control the retainer.

The presser-foot mechanism, in so far as it is pertinent to the present application, is shown particularly in Figs. 4, 5, 6 and 7. The presser-foot 16 is carried by a lever 38 45 which rocks on a pivot-stud 40, the rocking movement being for the purpose of varying the distance of the presser-foot from the work-support. The lever 38 has a rearwardly-projecting arm 42 upon which a ratchet-block 44 is fixed. This ratchet-block co-operates with pawls 46 pivoted on the frame of the machine and controlled by springs 48. The pressure of the presser-foot against the work is produced by mechanism including a lever 50, which is also mounted on the pivot 40 and is actuated by means of a pawl 52 carried by a cam-lever 54. All of the parts of the presser-foot mechanism just described are similar to those shown in said patent, and their construction and operation need not be further described. It will be understood, however, that when it is necessary for the operator to raise the presser-foot from the work, for the purpose 60 of permitting removal or replacement of

the work, it is necessary first to swing the pawls 46 and 52 rearwardly out of engagement with the co-operating ratchets, in order to release the presser-foot.

In certain machines, constructed otherwise like that shown in said Patent No. 473,870, the releasing of the presser-foot and the raising of the presser-foot are distinct operations, produced by two independently movable devices. A similar construction is employed in the present case, though with additions which simplify its operation. For the purpose of moving the presser-foot an arm 55 is fixed to the lever 38, extending upwardly therefrom. By 70 pressing this arm rearwardly the lever and the presser-foot may be swung upwardly. For the purpose of releasing the presser-foot a lever 56 is pivoted on the stud 40, and a push-member 58 is pivoted to the lower 75 end of the lever 56. The member 58 is forked, and its upper branch 60 engages a pin 62 projecting laterally from the pawl 52. When the upper arm of the lever 56 is drawn forwardly the pin 62 is pressed 80 rearwardly, thus swinging the pawl 52 to inoperative position, as shown in Fig. 7. Similar means are employed to trip the pawls 46, the member 58 having a lower branch 64 which engages a pin 66 by which 85 the pawls may be tripped in the same manner as the pawl 52.

As so far described the construction is not novel, but a feature of the present invention resides in the use of means by which the two 90 operations involved in releasing and lifting the presser-foot, namely, the forward movement of the lever 56 and the rearward movement of the arm 55, are produced by a single manual movement. As shown in Figs. 6 and 105 7, the lever 56 is normally retained in its inoperative position by a spring 68, which connects the lever with a lug 70 projecting from a member 72 of the frame of the machine. The lever is also provided with a 110 short arm 74, which co-operates with a stop-lug 76 projecting from the frame-member, whereby forward movement of the lever is limited. The release-lever 56 and the lifting-arm 55 are actuated in sequence by a 115 lever 78 of bell-crank form. This lever is connected, at its lower point, with the upper end of the release-lever 56, by means of a pivot 80. The uppermost point of the bell-crank lever is provided with a pivot 120 stud 82, to which is attached a head 84 at the forward end of a guide-rod 86. This guide-rod slides through an opening in the casing 20, and is provided with stop-nuts 88 to limit its forward movement. Rearward movement of the guide-rod is resisted by a compression-spring 90 coiled around the rod. A branch 92 of the lever 78 projects forwardly and is employed to actuate the lever. If this branch 92 be pressed up- 125

wardly, in any convenient manner, the lever tends to rock in such a direction as to press the guide-rod 86 rearwardly and pull the release-lever 56 forwardly. The relative strength of the various springs before described is such that the spring 90 at first effectually prevents rearward movement of the guide-rod, so that the stud 82 constitutes the fulcrum about which the lever at first moves, with the result that the release-lever 56 is swung forwardly and the pawls are tripped. If the rocking movement of the lever 78 be continued, however, the movement of the release-lever is arrested by the engagement of the stop-arm 74 with the stop-lug 76. The pivot 80 then becomes the fulcrum upon which the lever 78 thereafter moves, so that the stud 82 swings rearwardly, compressing the spring 90. This rearward movement causes the stud to engage the lifter-arm 55 and swing this arm rearwardly, thus rocking the presser-foot lever 38 and raising the presser-foot, as shown in Fig. 7.

The construction just described constitutes a convenient means by which a presser-foot mechanism, organized so as to require two distinct manual operations for the purpose in question, may be modified so that the presser-foot may be released and raised by a single manual operation, and in this aspect the present invention is applicable generally to machines having presser-foot mechanisms so organized. The present invention is particularly adapted, however, for use in connection with a machine provided with a front-cover which incloses the presser-foot mechanism. In such an arrangement it is desirable to provide means accessible from the outside of the cover for releasing and lifting the presser-foot, so that this may be done without opening the cover. In the present instance manually-operable means for this purpose are provided, which are supported directly upon the cover in such a position that they may coöperate with the presser-foot mechanism normally inclosed within the cover. A manually-operable arm 94 is provided with a shank 96 which turns in a bearing in the cover 22, and a second arm 98 is fixed to the inner end of the shank. The extremity of the arm 98 is so located that when the cover is in closed position this extremity lies directly beneath the branch 92 of the lever 78. Accordingly, when the cover is closed, if the arm 94 be pressed rearwardly by the operator of the machine, the arm 98 swings upwardly and raises the branch 92, thereby causing the presser-foot to be released and lifted by the operations previously described.

The arrangement herein described of the retainer 34, in connection with the cover 22, is particularly useful in connection with the problem of applying a casing and a front-

cover to the specific machine disclosed in said Patent No. 473,870, but it will be apparent that various features of the invention disclosed and claimed herein are applicable to machines of other types, and that the invention is not, in general, limited to the embodiment thereof hereinbefore described and illustrated in the accompanying drawings, but that it may be embodied in various other forms within the scope of the following claims.

What is claimed is:

1. A two-thread sewing-machine having, in combination with sewing-instrumentalities including a holder, for locking-thread, so accessible at the front of the machine: a cover, for inclosing forward parts of the machine; and a retainer for said holder united with said cover so as to coöperate with the holder when the cover is in operative position.

2. A lock-stitch sewing-machine having, in combination, a shuttle-race; a shuttle therein, open forwardly; a thread-case in the shuttle; a cover for inclosing forward parts of the machine, pivotally mounted so that it may be swung to inoperative position to afford access to parts normally inclosed thereby; and a thread-case retainer united with said cover so as to be moved into and out of operative position with the cover.

3. A sewing-machine having, in combination, sewing-instrumentalities including a presser-foot; a forwardly-movable releasing-lever for the presser-foot; a rearwardly-movable lifting-lever for the presser-foot; a cover normally inclosing forward parts of the machine including said levers; a manually-operable device carried by the cover and accessible from the outside thereof; and connections, between said device and said levers, for actuating the levers.

4. A sewing-machine having, in combination, sewing-instrumentalities including a presser-foot; a forwardly-movable releasing-lever for the presser-foot; a rearwardly-movable lifting-lever for the presser-foot; a cover normally inclosing forward parts of the machine including said levers; a manually-operable device carried by the cover and accessible from the outside thereof; and connections, between said device and said levers, for actuating the levers, including an operating-lever, inclosed within the casing, which has points of engagement with the manually-operable device, the releasing-lever, and the lifting-lever, respectively.

5. A sewing-machine having, in combination, sewing-instrumentalities including a work-holding device; a member for releasing the work-holding device; a separately movable member for moving the work-holding device to inoperative position when so released; a cover normally inclosing parts

of the machine including said members, a manually-operable device carried by the cover and accessible from the outside thereof; and connections, between said device and said members, effective when the cover is in its normal position and constructed and arranged to transmit a single movement of the manually-operable device successively to said members to first release 10 the work-holding device and then move it to inoperative position.

6. A sewing-machine having, in combination, sewing-instrumentalities including a presser-foot, a forwardly movable releasing- 15 lever for the presser-foot, a rearwardly

movable lifting-lever for the presser-foot, an actuating-device, and connections, between said device and said levers, for actuating said levers successively to first release and then raise the presser-foot. 20

7. A sewing machine, having, in combination, sewing instrumentalities including a work holding device, a releasing member and a lifting member movable in opposite directions, a yielding support separate from the work holding device, and an actuating device movable on said support to actuate said releasing member and movable with said support to actuate said lifting member. 25

THOMAS H. SEELY.
